UNITED STATES PATENT OFFICE

2,436,477

CLOTHESLINE STRETCHING DEVICE

Richard C. Lewis, Chicago, Ill.

Application March 1, 1946, Serial No. 651,126

3 Claims. (Cl. 211—119.15)

1

My invention relates to a device adapted to take the slack out of a clothesline and hold it in taut condition.

Among the objects of my invention is to provide a clothesline stretcher which will permit a line to extend between two points without the need of intermediate supports. My device is also adapted to stretch several lines. It operates from the extreme end of my stretcher and needs no extraneous complicated levers. My device is economical to manufacture, lasting in use, simple and efficient in operation, and has such other objects, advantages, and capabilities as will later more fully appear and which are inherently possessed by my invention.

While I have disclosed herein preferred embodiments of my invention, yet I wish it understood that the same is susceptible of modification and change without departing from the spirit of my invention.

Referring to the drawings, Fig. 1 is face view of one embodiment of my device; Fig. 2 is a perspective view and Fig. 3 a detailed sectional view; Fig. 4 is a perspective view of another embodiment of my device; and Fig. 5 is a reduced elevational view of my device in use.

An embodiment selected to illustrate my invention comprises a pair of spaced side rails 10 and 11, a fixed top member 12 extending between and slightly spaced from said rails 10 and 11, and a bottom member 14 extending between and attached to said rails 10 and 11. Said side rails 10 and 11 are pivotally attached to top member 12 by suitable pins 13. The bottom edge of my bottom member 14 has a plurality of spaced slots 15. A substantially centrally located outwardly extending detent 16 is anchored in the bottom edge of said bottom member 14.

The above described stretcher 17 is attached by suitable means such as nails 18 to a post, tree, wall, porch, or other suitable support 19. Also attached to support 19 by suitable means such as nails 20 is retaining member 21, which has a right angled forwardly extending portion 22. Retaining member 21 being of metal or the like, forward portion 22 is resilient. Cut out in forward portion 21 is a tear drop shaped opening 23.

In use, a clothes line 24 is attached at one end to a suitable support 25 and extends to and through loop or clip 26 which is attached to a suitable support 19. The clothes line 24 is provided with knot 28 and placed in one of slots 15, the knot 28 preventing undesired removal. Side rails 10 and 11 and bottom member 14 are pivoted downwardly, taking up slack in the clothesline 24.

2

and making it taut. When detent 16 strikes retaining member 21, forward portion 22 yields under pressure so that detent 16 enters opening 23 at the higher, larger part of the opening. Pressure is then released and pressure of the clothes line forces detent 16 into the lower smaller portion of opening 23 to hold the detent and the stretcher.

10 A slightly different embodiment of my stretcher comprises a single length of metal forming one side rail 30, bent at the bottom of the rail and extending transversely with spaced indentations forming slots 31, and then bent upwardly to form the opposite side rail 32. A support 33 extends 15 between and is attached to rails 30 and 32 at their lower portions. An upper member 34 has ears 35 to which are pivotally attached the rails 30 and 32 at their upper portions, by means of a pin or rivets 36.

20 Having thus described my invention, I claim:

1. A clothesline stretching device comprising a stretcher having a fixed upper member adapted to be attached to a support, a pair of spaced side rails pivotally attached to said upper member, a bottom member attached to the lower portions of said side rails, said bottom member having at its bottom portion a plurality of clothesline receiving slots, and a detent attached to said bottom member, and a holding member attached to 25 a support and having a resilient tongue with a tear shaped opening therein, said tongue positioned and adapted to be contacted by said detent and to yield to removably receive said detent within said tear shaped opening, and hold said stretcher.

2. A clothesline stretching device comprising an upper fixed portion adapted to be attached to a support, a pivot portion pivotally attached to said upper fixed portion, a lower portion attached 40 to said pivot portion and having means to receive a plurality of clotheslines at its lower end, a detent attached to said lower portion and a retaining member attached to a support, and having a resilient tongue with a tear shaped opening 45 therein, said tongue positioned and adapted to be contacted by said detent and to yield to removably receive said detent within said tear shaped opening, and hold said stretcher.

3. A clothesline stretching device comprising an 50 upper fixed portion adapted to be attached to a support, a pivot portion pivotally attached to said upper fixed portion, a lower portion attached to said pivot portion and having means at its lower end to hold a clothesline, a detent attached to the lower end of said lower portion and a resilient

retaining member attached to a support, and having means to removably receive said detent and hold said stretcher.

RICHARD C. LEWIS.
